UNITED STATES PATENT OFFICE.

EVA CLEWELL, OF WILKESBARRE, PENNSYLVANIA.

COMBINED SKIRT-SUPPORTER AND PLACKET-FASTENER.

SPECIFICATION forming part of Letters Patent No. 767,869, dated August 16, 1904.

Application filed December 7, 1903. Serial No. 184,162. (No model.)

To all whom it may concern:

Be it known that I, EVA CLEWELL, a citizen of the United States, residing at Wilkesbarre, in the county of Luzerne and State of Pennsylvania, have invented a new and useful Combined Skirt-Supporter and Placket-Fastener, of which the following is a specification.

This invention relates to attachments for garments for fastening the plackets and suspending the garment thus connected from the belt or waistband or from a shirt-waist, and has for its object to simplify and improve the construction of such devices and to produce an article which may be readily attached to the garments and easily connected and disconnected and which will hold the garments securely in place and not be liable to disarrangement while in use.

The invention consists in certain novel features of construction, as hereinafter shown and described, and specified in the claims.

In the drawings illustrative of the invention, in which corresponding parts are denoted by like designating characters, Figure 1 is a perspective view of the device applied. Fig. 2 represents the three parts forming the device in perspective and disconnected.

The improved device comprises three parts, a plate for attachment to the belt or waistband and two plates for attachment to the opposite flaps of the placket of the skirt or other garment to be fastened and supported, the two placket-plates adapted for detachable connection to the belt or waistband plate.

The belt or waistband plate is represented at 10 and provided with means, such as spaced perforations, for sewing to the belt or waistband 11 and formed with oppositely-extending spaced hooks 12 13, as shown, and will be located on the outer surface of the belt or band opposite the "placket" of the garment which is to be fastened and suspended.

The placket-plates are represented at 14 15 and are precisely alike and provided, respectively, at one end with elongated apertures 16 17 and adapted for attachment in reverse

order, as by sewing to the opposite flaps 18 19 of the placket of the skirt or other garment, (represented at 21.)

One of the placket-plates will be attached 50 to the interior of the flap, and the other will be attached to the exterior, as shown, and will be coupled to the waistband or belt by placing the elongated aperture 16 over the hook 13 from one side and the elongated aperture 55 17 over the hook 12 from the opposite side, each aperture thus receiving both hooks and the plates all lying in superimposed position when in action and the adjacent edges of the flaps 18 19 overlapping and lying close together. By this simple arrangement the garments will be very firmly held closely united, with no danger of displacement, no matter how severely the wearer may move about or strain the body.

The parts will preferably be struck up from sheet metal of requisite thickness and strength and may be varied in size to suit different forms and sizes of garments.

The device supports the skirt or other garment and avoids all sagging and does not add materially to the expense or weight.

Having thus described the invention, what I claim is—

1. A combined placket-fastener and skirt-support, comprising a plate for attachment to a supporting-garment and provided with laterally-spaced, reversely-disposed hooks arranged in alinement, and plates for attachment to the opposite flaps of a skirt-placket, 75 each plate being provided with an elongated aperture extending longitudinally thereof through which said hooks are adapted to project, one of the hooks engaging the end of one plate and the other hook engaging the end of 80 85 the other plate.

2. A combined placket-fastener and skirt-supporter comprising a plate having means for attachment to a supporting-garment and provided with oppositely-extending arms bent 90 at an angle to said plate and having their free ends bent to form reversely-disposed hooks,

a plate for attachment to the inner surface of one of the placket-flaps and provided with an elongated longitudinally-disposed aperture through which both of said hooks extend and 5 with which one of said hooks engages, and a plate for attachment to the outer surface of the other placket-flap and provided with an elongated longitudinally-disposed aperture through which the hooks project and with the

end wall of which the other of said hooks engages.

In testimony that I claim the foregoing as my own I have hereto affixed my signature in the presence of two witnesses.

EVA CLEWELL.
